HEATING AND AIR CONDITIONING SYSTEM
Maurice W. White, Medford, Oreg., assignor to Frigid-
Heat Corporation, a corporation of Oregon
Filed Sept. 10, 1964, Ser. No. 395,400
2 Claims. (Cl. 62—118)

The present invention generally relates to a heating and air conditioning system that is particularly adapted for heating and air conditioning spaces having a heat load such as supermarkets, stores and the like having individual refrigeration systems with condensing units incorporated therein which give up heat to the space. The present invention involves a novel method of removing heat from such store condensing units with the present invention further providing a system having an operating range on its heat removal for store refrigeration units whereby the owner or operator of the store will realize greater efficiency from his refrigeration equipment.

In an average supermarket or food store, there is a heat rejection capacity from display cases, storage coolers and the like normally in excess of 400,000 B.t.u.'s per hour. In the interest of efficiency, it is desirable to make use of this heat if economically possible. Accordingly, it is an object of the present invention to use this heat. Further, in most all supermarkets, it is also necessary to have heating and air conditioning. In systems where supermarkets have a gas fired heating system, an oil fired heating system or some other method of heating, the air conditioning compressor sets idle for several months of the year. In some areas, the air conditioning compressor will be idle for six to eight months of the year. In the present invention, the store air conditioning unit is incorporated into the air conditioning system as an auxiliary heating system so that when the store space is being heated with the normal warm condensing water from the condensing units of the display cases and the like and the outside temperature is quite low, the store space air conditioning unit is brought into use in a reverse or heat cycle to take additional heat from the condenser water of the condensing units of the display cases and the like. Thus, the present system provides a substantial heat output and at the same time, the store owner or operator gains constant operating pressures the year around for his store space air conditioning system thereby reducing compressor maintenance to a minimum.

Thus from the foregoing, it will be understood that one of the objects of the present invention is to provide a heating and air conditioning system particularly adapted for use in supermarkets that is efficient in operation, dependable and long lasting, relatively inexpensive to install and effective to reduce the over-all cost of heating and cooling a supermarket, food store or the like.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a schematic view of the heating and air conditioning system of the present invention with the heating and air conditioning unit being separated into two units for clarity, it being pointed out that these two units are actually in one package; and

FIGURE 2 is a sectional view taken generally upon a plane passing along section line 2—2 of FIGURE 1 illustrating that the two units are disposed in one package with the units at the right hand of FIGURE 1 being dis-

2

posed alongside of each other as illustrated in FIGURE 2.

Referring now specifically to the drawings, the heating and air conditioning system of the present invention is generally designated by the numeral 10 and is disposed exteriorly of a building whose wall is schematically illustrated at 12 and this wall may be either the ceiling or wall of a store or supermarket. Disposed interiorly of the wall 12 within the store space, there is provided a heat exchange coil unit 14 having a fan 16 associated therewith for circulating air through or over the heat exchange coil 14 within the store space. The particular details of construction of the various components of the present invention are conventional in and of themselves except where otherwise specifically defined. In this instance, the coil unit may be of any suitable structure such as a finned tube-type having any suitable housing or shroud and any suitable mechanism for supporting the same.

The evaporative condensing unit is illustrated in FIGURE 1 in two sections as a right hand section 18 and a left hand section 20 which when joined together form a single unit as illustrated in FIGURE 2. In the upper end of each part of the condenser unit there is provided a water coil 22 having a plurality of spray heads 24 orientated thereover that are communicated with a spray water pump 26 by a water line 28 with the pump 26 having a suction line 30 extending into the interior of the condenser unit above an inner bottom 32 which collects the water from the spray heads or nozzles 24 with a float valve 34 being provided for maintaining a predetermined water level 36 within the upper compartment defined by the inner bottom 32. Thus, water may circulate from the sump defined above the inner bottom 32, through the pump 26 and through the spray nozzles 24 over the coils 22 and back into the sump in an obvious manner.

Disposed below the inner bottom 32 is a refrigerant coil 38 disposed between an outer bottom 40 and the inner bottom 32 in a lower compartment. This compartment extends beyond one end of the upper compartment into a substantially L-shaped area 42 and a heat sensing bulb 44 is provided therein adjacent the refrigerant coils 38. A water pump 46 has a suction line 48 communicated with the lower end portion of the compartment receiving the refrigerant coils 38 and has a discharge line 50 connected with the water coil 22. The compartment 42 is provided with a water filler tube 52 communicated therewith and the water coil 22 has a water line 54 extending into a condensing unit 56 with a water service valve 58 being incorporated therein. A magnetically operated valve 60 is employed in the water line 50. A by-pass line 62 interconnects the lines 50 and 54 with a magnetic valve 64 being incorporated therein so that water pumped by the pump 46 may either pass through the coil 22 or by-pass the coil 22 for entry into the condenser unit 56. Also, the condensing unit 56 is provided with a water line 66 having a by-pass line 68 connected thereto and provided with a magnetic valve 70 so that water may pass from the condensing unit 56 back through the pipe 52 into the compartment 42 or pass on to the heat exchange coil unit 14 and then return to the filler tube 52 through a water line 72.

An air fan 74 is provided at one end of the evaporative condenser unit and this fan may be in the form of a conventional blower for circulating air through the evaporative condenser unit for additionally cooling the water heat exchange medium circulated by pump 26.

The refrigerant system includes a receiver tank 76 communicated with an expansion valve 78 which discharges refrigerant to the refrigerant coil 38 as controlled by the

sensing bulb 44 or the like. A by-pass line 80 having a check valve 82 therein is provided around the expansion valve 78 and a refrigerant line 84 extends from the expansion valve 78 to the receiver tank 76 with there being a service valve 86 incorporated therein for servicing the refrigerant system. Thus, from the receiver, the refrigerant may pass through the expansion valve into the refrigerant coils 38 in a conventional manner. Refrigerant is returned from the evaporative coil 38 through refrigerant line 88 into a four-way valve 90 for communication through refrigerant lines 92 to the air conditioning condensing unit 94 which also has a refrigerant line 96 extending back to the four-way valve 90 which enables the refrigerant to be circulated through the refrigerant coil 38.

It is pointed out that the upper and lower half of FIGURE 1 should actually be superimposed upon each other and the structure or arrangement of components as illustrated in both halves of the device with the upper half being primarily concerned with the water circulation while the lower half is primarily concerned with the refrigerant circulation.

In describing the system, attention is directed initially to the upper part of FIGURE 1 relating to the heating system in which the pump 46 circulates warm water through line 50 to the valve 60 which enables the tower to be bypassed if the water is not hot enough for the tower to be used. At that time water either goes through the coil 22 or it can be by-passed into the water line 54 through the valve 64 and by-pass line 62 directly into the condensing unit 56. There may be as many as seventeen or eighteen condensing units 56 and at this point, the water takes on heat from the condensing units 56 in a conventional manner. If at that time, heat is called for in the store, the heated water passes through line 66 into the room heat exchange unit 14 and thence back through line 72. However, if heat is not called for in the store space, the heated water is by-passed through magnetic valve 70 and by-pass line 68 where it is discharged back into the sump or compartment 42 on the bottom of the closed circuit tower for heat exchange engagement with the refrigerant coils 38.

If heat in addition to that which can be supplied by the store condensing units 56 is required, the condenser unit 94 of the air conditioning system comes on in a reverse cycle or heating cycle and heats water in the sump 42 by virtue of the hot refrigerant gas passing into the refrigerant coil 38 without passing through the condenser and expansion valve. Thus, the water which is heated in compartment 22 may be pumped through the store coil unit 14 in the same manner as discussed in conjunction with the water which was heated by the condensing unit 56. When the outside temperature gets above 15° F., the compressor condenser unit 94 in the air conditioning system will cut off automatically by suitable control mechanism and the total heating is then done by condenser water only which is heated by the condensing units 56. In a considerable number of localities, total heating can be done by the condensing units of the storage cabinets, cooling cabinets or the like designated at 56 thus making the store operator's heating cost very low with the total cost being operation of the fan 16.

The air conditioning system which provides heat to the compressor condenser unit 94 is a normal arrangement including a reversing valve and becomes a chiller in the summer when air conditioning is needed. The specific part of the present invention which renders it novel is the method of pumping warm water from the sump under the closed circuit tower to one circuit of the store unit 14, removing the heat from that water by the circulating fan 16 and then returning this same water back to the opposite side of the sump and removing additional heat by refrigeration and then heating the circulated water on the other side of the bottom sump for heating the second circuit of the room coil unit 14 which is schematically illustrated in FIGURE 1 with the lines leading to the second unit being designated by numerals 98 and 100.

Thus, by using the air conditioning compressor and condensing system during normal periods of non-use, compressor maintenance is reduced and by operating the air conditioning compressor, condenser evaporative unit in a reverse cycle as a heat pump will produce additional heat with this output of heat being substantially increased by feeding heat into the low side of the condensing unit.

An alternative method of procedure would involve using the water returned in line 72 from the heat exchange coil unit 14 and either heating or cooling, depending on cycle, refrigerant which in turn is pumped through line 98 to refrigerant oil which replaces existing secondary water coil in store unit. In such an arrangement, an additional water pump would be added to pump water from sump 42 to store coil unit 14. This procedure would involve replacing refrigerant coil 38 with a coil located in sump 42. This coil would be utilized for heating cycle. This procedure would eliminate all magnetic by-pass valves and the pump would be operated thermostatically.

In considering the detailed disclosure and the modification thereof, and disclosed construction, warm water that is heated from the store condensing unit that is used in refrigeration systems for storage cabinets which are cooled, freezer cabinets and the like is conveyed to the interior of the store for giving up heat to the interior of the store. When the outside temperature reaches a determined minimum, the air conditioning system for the store is operated in reverse cycle. The heated circulating water which has passed from the heat exchanger associated with the store condensing units and then passes through the heat exchanger in the store itself has residual heat which is captured or utilized by the evaporative coil of the air conditioning system which is in reverse cycle thus giving up heat to the evaporative coil for rendering the reverse cycle of the air conditioning system more efficient in operation and enormously increasing the output thereof so that the store may be effectively heated by the heat produced by the condensing units for the cooling cabinets in the store and also by heat produced by the air conditioning system in reverse cycle thereby enabling waste heat to be effectively employed and also to enable existing air conditioning equipment that would normally be idle to be effectively employed for heating the store.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. The method of heating and air conditioning a building such as a food store or supermarket having cooling devices therein employing a refrigeration system and producing a heat rejection load consisting of the steps of collecting the rejected heat load in a heat exchange medium at a point exteriorly of the space in which the heat rejection load is produced, conveying the heat exchange medium to the space in which the heat rejection load was produced, passing the heat exchange medium through a heat exchange coil in the space, and passing air over the heat exchange coil for heating the space in which the heat rejection load was produced.
2. The method as defined in claim 1 together with the steps of operating an air conditioning system for the building in reverse cycle when exterior temperature reaches a predetermined low temperature, and conveying the air cooled heat exchange medium from the heat exchange coil in the space in which the heat rejection load was produced to the evaporator of the air conditioning refrigeration system having an evaporator and condenser operating in a reverse cycle thereby enabling the condenser of the reverse cycle air conditioning system to have a higher heat output,

and adding the heat output of the reverse cycle air conditioning system to the heat exchange medium.
